CLAIM

The ornamental design for a wireless communication device, as shown and described.

DESCRIPTION

FIG. 1 is a side perspective view of the wireless communication device showing my design with the flip cover in an open position;

FIG. 2 is a front view thereof;

FIG. 3 is a front view of an alternate embodiment of my design for the wireless communication device;

FIG. 4 is a front view of the wireless communication device illustrating the flip cover in a closed position overlying a portion of the body of the wireless communication device, with the antenna in a stow position;

FIG. 5 is a side view thereof;

FIG. 6 is an opposing side view thereof;

FIG. 7 is a top end view thereof;

FIG. 8 is a bottom end view thereof; and,

FIG. 9 is a rear view thereof.

FIGS. 2 and 3 illustrate the antenna longitudinally extended a distance away from the body of the wireless communication device. FIGS. 4-9 correspond to both embodiments of the design, as shown in FIGS. 2 and 3, respectively, except that the antenna is shown in FIGS. 4-9 in a stow position.

1 Claim, 4 Drawing SheetsFIG. 1.

FIG. 2.

FIG. 3.

FIG. 4.

FIG. 5.

FIG. 6.

FIG. 7.

FIG. 8.

FIG. 9.
